BICYCLE SEAT

Albert J. Fritz, Northbrook, and Anton J. Panzica, Hinsdale, Ill., assignors to Schwinn Bicycle Company, Chicago, Ill.

Filed Dec. 31, 1970, Ser. No. 26,724

Term of patent 14 years

Int. Cl. D12—16
U.S. Cl. D90—16

FIG. 1 is a perspective view of a bicycle seat showing our new design;

FIG. 2 is an enlarged rear elevational view thereof;

FIG. 3 is a top plan view thereof;

FIG. 4 is a side elevational view thereof;

FIG. 5 is a front elevational view thereof; and

FIG. 6 is a bottom plan view thereof.

We claim:

The ornamental design for a bicycle seat, substantially as shown and described.
